[57] **CLAIM**

The ornamental design for a handle for folding pocket
knife, as shown and described.

DESCRIPTION

FIG. 1 is a perspective view of a handle for folding
pocket knife showing my new design, the blade being
shown in broken lines for illustrative purposes only;

FIG. 2 is a side view thereof, the opposite side being a
mirror image;

FIG. 3 is a top view thereof;

FIG. 4 is a bottom view thereof;

FIG. 5 is an end view thereof; and

FIG. 6 is an opposite end view thereof.
